WILLIAM J. A. LONDON, OF HARTFORD, CONNECTICUT, ASSIGNOR TO THE WESTINGHOUSE MACHINE COMPANY, A CORPORATION OF PENNSYLVANIA.

ELASTIC-FLUID TURBINE.

972,788.

Specification of Letters Patent.

Patented Oct. 11, 1910.

Original application filed March 6, 1906, Serial No. 304,477. Divided and this application filed February 19, 1909. Serial No. 478,933.

To all whom it may concern:

Be it known that I, WILLIAM J. A. LONDON, a subject of the King of Great Britain, and a resident of Hartford, Connecticut, have invented new and useful Improvements in Elastic-Fluid Turbines, of which the following is a specification, this application being a division of an application filed by me on March 6, 1906, Serial No. 304,477.

10 This invention relates to elastic fluid turbines and has for an object the production of means for counterbalancing the end or longitudinal thrusts on the rotors of turbines of the axial-flow multi-stage type.

15 A further object is the production, without the use of balancing dummy pistons, of a balanced turbine, through the major portion of which the motive fluid flows in one axial direction only.

20 Turbines of the axial-flow multi-stage type are ordinarily balanced by means of dummy pistons which are so mounted on the turbine rotor and to which the motive fluid is so delivered that the longitudinal thrust 25 of the motive fluid on the dummies counterbalances the longitudinal thrust occasioned by the motive fluid in the working passages of the turbine.

25 My invention contemplates so proportioning the diameters of the blade-carrying drums of the separate stages of the turbine and so arranging the stages relative to the flow of motive fluid that the longitudinal thrusts on the turbine rotor will be counterbalanced without the necessity of utilizing balancing dummies.

30 The embodiment of my invention herein described and illustrated comprises a multi-stage turbine of the axial-flow type which is divided into a high-pressure stage and a low-pressure stage.

35 The blading of the high-pressure stage is mounted on a drum or equivalent part in the usual manner; the blading and the fluid passages of the low-pressure stage are, however, so arranged that the fluid exhausting from the high-pressure or initial stage and entering the low-pressure stage is divided into two parts and the separate portions are 40 caused to flow in opposite directions while traversing the low-pressure stage. The fluid passages of the low pressure stage and the rotor element are so arranged that the axial or longitudinal thrust exerted by one por-

tion of the motive fluid traversing the low-pressure stage is counter-balanced by an opposing axial thrust by the motive fluid traversing the high-pressure stage and one portion of the low-pressure stage.

45 The drawing accompanying this application and forming a part thereof is a longitudinal section of a turbine embodying my invention.

50 Referring to the drawing: the rotor element comprises a high-pressure drum 2 and a low-pressure drum 3 and is suitably mounted on shafts 4 which project through the ends of the turbine casing 5 and which are provided with suitable journals (not shown). The shafts 4 are secured by suitable means to each end of the drum 2 and the drum 3 is suitably mounted on the drum 2. The casing 5 incloses the rotor and is provided with a fluid inlet port 6 and a fluid exhaust port 7 and is so constructed that 55 fluid passages of proper area are maintained between it and the rotor element.

55 Alternate rows of stationary vanes 8 and moving blades 9 are mounted on the casing and the drum 2 respectively and comprise 60 the high-pressure stage of the turbine. The blades and vanes are adapted to fractionally expand the motive fluid supplied to them and to abstract the energy rendered available by the expansion by impulse and re- 65 action.

70 The admission port 6 communicates with an annular passage 10 which is formed within the casing and is located at one end of the rotor element and which is adapted 75 to deliver motive fluid to the vanes and blades of the high-pressure stage.

75 The low-pressure stage is divided into two sections through which the motive fluid flows in opposite directions. One section 80 comprises vanes 11 mounted on the casing and blades 12 co-operating therewith and mounted on a portion of the drum 3. The other section comprises vanes 13 mounted on the casing and blades 14 mounted on a flange 100 15 of the drum 3. The flange 15 is of enlarged diameter and the drum 3 is so formed that an annular passage 16 is located between the section of enlarged diameter of the low-pressure stage and the exhaust end 105 of the high-pressure stage.

85 The vanes 11 and the blades 12 of the low-pressure stage receive motive fluid from

an annular passage 17 located between the rotor and the casing and communicating directly with the exhaust end of the high-pressure stage. The vanes 13 and blades 14 of the low-pressure stage receive motive fluid from the annular passage 17 through the passage 16 which is formed within the drum 3.

The motive fluid entering the series of 10 vanes 11 and blades 12 is expanded to vacuum or exhaust pressure and is discharged into an annular passage 18 which communicates with the exhaust port 7. The motive fluid traversing the series of vanes 15 13 and blades 14 is expanded to vacuum or exhaust pressure and is discharged into the annular passage 18.

The longitudinal thrust of the motive fluid on the rotor element is counterbalanced by proportioning the diameter of the flange 15 so that the total pressure of the fluid exhausted from the high-pressure stage and acting on the face 19 of the drum 3 plus the resultant pressure of the fluid traversing the blades 14 and the pressure of the motive fluid on the adjacent end of the drum 2 will counter-balance the longitudinal thrust on the rotor occasioned by the high-pressure motive fluid in the passage 10, 25 the resultant pressure of the motive fluid traversing the high-pressure stage and the longitudinal pressure of the motive fluid traversing the blades 12 of the low-pressure stage. With such an arrangement the longitudinal thrusts on the rotor element are 30 counterbalanced. In cases where the load on the turbine is suddenly changed, there probably would be a momentary end thrust, which may be taken up with a suitable 35 thrust block or piston which is common in the art and is not shown.

In accordance with the provisions of the patent statutes, I have described the principle of operation of my invention, together 45 with the apparatus which I now consider to represent the best embodiment thereof, but I desire to have it understood that the apparatus shown is only illustrative and that the invention can be carried out by other 50 means.

What I claim is:

1. In an elastic fluid turbine, a full peripheral admission axial-flow high-pressure stage, a divided stage of lower pressure and a passage in the turbine rotor for placing 55 the inlets of said low-pressure stage in communication one with the other and with the outlet of said high-pressure stage.

2. In an elastic fluid turbine, one or more stages through which the fluid flows in one 60 direction only and a divided low-pressure stage, the divisions of which are of different diameters for the purpose of counterbalancing the axial rotor thrusts and through the divisions of which the motive fluid flows in 65 opposite directions.

3. In an elastic fluid turbine, one or more stages through which the motive fluid flows in one axial direction only and a divided 70 low-pressure stage comprising sections of 70 different diameters located at one end of said turbine and through which the motive fluid flows in opposite directions.

4. In an elastic fluid turbine, one or more stages through which the motive fluid flows 75 in one axial direction only and a low-pressure stage comprising sections of different diameter through the sections of which the fluid flows in opposite axial directions.

5. In an elastic fluid turbine, one or more 80 stages through which the motive fluid flows in one axial direction only and a blade-carrying member of greater diameter than any of the stages and between the blades of which the motive fluid flows in an opposite 85 direction to the motive fluid flowing through said stages.

6. In an elastic fluid turbine, an initial stage and a stage of lower pressure receiving motive fluid exhausted from the initial stage 90 and divided into two sections of different diameters through which the motive fluid flows in opposite directions.

In testimony whereof, I have hereunto 95 subscribed my name this 16th day of February, 1909.

WILLIAM J. A. LONDON.
